(57) **CLAIM**

The ornamental design for a napkin holder as shown and described.

DESCRIPTION

FIG. 1 is a front elevation view of a napkin holder, showing my new design, of which the rear elevation view is identical; FIG. 2 is a top plan view thereof in a closed configuration; FIG. 3 is a top plan view thereof in an open configuration; FIG. 4 is a bottom plan view thereof;

FIG. 5 is a left side elevation view thereof, in an open configuration, of which the right-side elevation view is identical;

FIG. 6 is a left side elevation view thereof in a closed configuration, of which the right-side elevation view is identical;

FIG. 7 is a left side elevation view thereof, with an environmental structure shown in broken lines, in an open configuration;

FIG. 8 is a left side elevation view thereof, with an environmental structure shown in broken lines, in a nearly closed configuration;

FIG. 9 is a front perspective view thereof, with an environmental structure shown in broken lines;

FIG. 10 is another perspective view thereof in an open configuration; and,

FIG. 11 is another perspective view thereof in a closed configuration.

The broken lines illustrate environmental structure and form no part of the claimed design.
